UNITED STATES PATENT OFFICE.

JOSEPH H. ALLIN AND ROBERT L. ALLIN, OF PECAN GAP, TEXAS.

ADJUSTABLE COLTER-CLAMP.

No. 856,200.

Specification of Letters Patent.

Patented June 11, 1907.

Application filed December 3, 1906. Serial No. 346,172.

To all whom it may concern:

Be it known that we, JOSEPH H. ALLIN and ROBERT L. ALLIN, citizens of the United States, residing at Pecan Gap, in the county 5 of Delta and State of Texas, have invented certain new and useful Improvements in Adjustable Colter-Clamps; and we do declare the following to be a full, clear, and exact description of the invention, such as will 10 enable others skilled in the art to which it appertains to make and use the same.

Our invention is an improved adjustable colter clamp, by means of which the standard of a colter may be securely fastened to a 15 plow beam of any construction, and may be adjusted as may be desired, and it consists in the construction, combination, and arrangement of devices hereinafter described and claimed.

20 In the accompanying drawings,—Figure 1 is partly a side elevation and partly a longitudinal sectional view of a colter clamp embodying our improvements, showing the same in operative relation to the beam of a plow and the standard of a colter; Fig. 2 is a transverse sectional view of the same; Figs. 3 and 4 are detail perspective views of the respective members of the clamp; Fig. 5 is a perspective view, showing the outer side of the 25 clamp member 2; and Fig. 6 is a transverse sectional view of our improved colter clamp, showing the same in operative relation to the beam of a plow and the cylindrical standard of a colter. Fig. 7 is a detail elevation of the 30 wedge block.

Our improved colter clamp comprises two members 1, 2, adapted to be placed on opposite sides of a plow beam, such as indicated at a, or of any other construction, and secured 35 thereto by bolts 3, 4. The section 1, which in practice is a casting, is provided at its upper side with a lateral bar 5 to extend above the beam and has at its lower end a lateral bar 6 to bear against the lower side of the 40 beam and provided with a depending flange 7. The bar 5 has a transverse dovetail slot 8 which is open at one end. On the outer side of the member 1 is an outwardly-projecting portion 9, provided with a vertical slot 10 extending therethrough from its upper to its 45 lower side, said slot being of such size as to enable it to receive the standard b of a colter and permit said standard to be disposed either in a vertical position or in an inclined position. In the outer side of the projecting portion 9 at the center thereof, is a screw-thread-

ed opening 11, in which is a set-screw 12 to bear against the other side of the standard b and clamp the same in place. In the front and rear sides of the said projecting portion 9 50 are similar openings 13 to receive screws 14, the said screws bearing against the front and rear edges of the colter and serving in connection with the screw 12 to securely hold the colter either in a vertical or in a forwardly 55 or rearwardly inclined position at any desired angle.

The section 2 has at its upper end a laterally-extending bar 15 to extend above the plow beam and has at its lower end a bar 16 60 to bear against the lower side of the plow beam and provided with a flange 17. The bolts 4 are placed in openings in the flanges 7 and 17, and the bolts 3 are placed in openings at the upper ends of the member 1, 2, 65 said bolts 3, 4, as hereinbefore stated, serving to clamp said members to opposite sides of the plow beam. The bar 15 of the clamp member 2 has on its upper side a dovetail shoulder 18 to enter and fit in the dovetail 70 slot 8 of the bar 5 of the member 1. It will be understood from the inspection of Fig. 2 of the drawings, that the upper lateral bars of the respective members 1, 2, are disposed in overlapped relation above the plow beam 75 and that the said members may be moved toward and from each other to narrow or widen the space between them and hence said members of the clamp may be firmly bolted on a plow beam of any construction whether 80 of wood, iron, or steel, and of any size.

We also employ a wedge block 19, which is inserted between the upper edge of the plow beam and the lateral bar 15 of the clamp member 2, to fill the space between the beam 85 and said bar and adapt the clamp to be attached to beams which vary in width vertically. The said wedge block has a series of depressions or seats 20 in the upper side for the reception of the lower end of a set-screw 21, which operates in a threaded opening in the bar 15 of the member 2. On the under side of the said wedge block are transverse, serrations 22 to engage the upper side 90 of the beam and insure a firm grip between 100 the wedge block and the beam.

To enable the clamp to be employed to secure a colter having a cylindrical standard c to the beam, we provide the clamp member 2 with an outwardly-extending, vertically-disposed portion 23 on its outer side, provided with a vertical, cylindrical slot 24 105

extending therethrough from its upper to its lower side, and of a suitable size to receive said standard *c*. Said portion 23 is provided with set-screws 25 to clamp the said stand-

ard.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention, as defined by the appended claims.

Having thus described our invention, what we claim as new, and desire to secure by Letters-Patent, is—

1. A colter clamp of the class described comprising a pair of members to engage opposite sides of a beam and provided with overlapping bars, one of said bars having a transverse slot and the other having a trans-

verse shoulder to engage said slot, means to

adjustably secure said members together and clamp them on opposite sides of the beam, one of said members having means, independent of the said securing and clamping means, to adjustably secure a colter stand- 30 ard to said member.

2. A colter clamp of the class described comprising a pair of members to engage opposite sides of a beam, one of said members having a vertical opening to receive the 35 standard of a colter, and further provided with means to receive said standard at any desired adjustment, and means independent of said standard receiving means, to clamp the said members on opposite sides of the 40 beam.

In testimony whereof we have hereunto set our hand in presence of two subscribing witnesses.

JOSEPH H. ALLIN.
ROBERT L. ALLIN.
